OXYGEN MASK

Walter M. Boothby and Arthur H. Bulbulian,
Rochester, Minn.

Application April 14, 1941, Serial No. 388,482

7 Claims. (Cl. 128—202)

Our invention relates to means for administering oxygen for breathing at varying altitudes and atmospheric pressures, and primarily is intended for the use of aviators, particularly military aviators, who have occasion to fly to great heights.

There is a direct relation between the pressure of oxygen in the alveolar regions of the lungs and the barometric pressure of the atmosphere in which the atmosphere at its barometric pressure is breathed. It further is true that when the alveolar oxygen pressure drops below a certain point serious pathological disturbances may result. In general barometric pressures corresponding to those up to elevations of 10,000 feet can be endured by most normal individuals without serious consequences. If the physical condition of an aviator is good he can withstand the anoxia or insufficient oxygen of the atmosphere he is breathing at pressure corresponding to elevations of 15,000 feet, perhaps as long as one hour. From such elevations up there is a rapidly decreasing endurance of anoxia and death may ensue at barometric pressures between 20,000 and 23,000 feet. It may be set forth that above 10,000 feet increases in elevation of every thousand feet greatly shortens the length of time the aviator can maintain his altitude with safety.

It is true, however, that in military aviation frequently much higher elevations must be entered even up to some 40,000 feet. Under such conditions there must be means afforded the aviator to supply additional quantities of oxygen in the lungs in order to raise the alveolar pressure of oxygen to a point approximating normal. It is further true that at the high elevations attained in military aviation intense cold is encountered and it is essential to have the oxygen supplying means so constructed that at least the exhalation valves will not become inoperative because of freezing. In practice oxygen may be supplied in a substantially closed circuit except for exhalation, in which case the exhalation valve alone must be protected from freezing. In other forms of apparatus inhalation of air also is provided by an inhalation valve in which case this valve also must be protected from freezing.

The use of masks and attendant apparatus in military aviation is further complicated by the fact that there are occasions when flying must be carried on with tremendously rapid descents from high altitudes to much lower altitudes, as in dive bombing, and the pressures encountered in such descents and particularly in the reversal thereof are so great that there is danger that mask apparatus may be torn from the aviator so

that when he returns to the high altitudes he will be subject to dangerous conditions of anoxia.

It is further essential that any mask structure worn by an aviator shall be provided with a microphone favorably located for radio transmission of the voice of the aviator, and this must be so related to the air passages and valves as they are constructed as not to interfere with ready and easy breathing.

10 It is a principal object of our invention therefore to provide against all these contingencies so that dependable apparatus is given the aviator such that he may be protected against any and all of the hazards above enumerated.

15 It is a further object of our invention to provide a mask structure which as worn will cooperate with the aviator's helmet to completely protect all parts of the face of the aviator below the eyes and which in conjunction with the aviator's goggles and helmet will in fact completely cover and protect the whole face of the aviator.

20 It is a further object of our invention to provide a mask wherein a portion thereof will extend below the chin of the aviator and will provide 25 means for securing the same upon the aviator's head such that the mask will resist the severe stresses in flying and diving above enumerated and remain in position under every conceivable exigency of altitude and flight.

30 It is a further object of our invention to provide a mask structure wherein a pair of turret devices adapted for any desired type of valve structure are symmetrically positioned on the face of the wearer and are provided with special 35 breathing channels connecting with outside tubes going to the reservoir rebreathing bag.

It is a further object of our invention to form the mask with side portions adapted to engage high up on the cheeks of the wearer, said side 40 portions extending into the part below the chin of the wearer and being formed with symmetrically disposed outward extensions provided with outwardly directed openings for connection of the 45 mask to the reservoir rebreathing bag as may be desired, with said breathing channels formed in the extensions.

It is a further object of our invention to provide, in conjunction with the two outlets from the mask, mechanism whereby the tubes to the reservoir rebreathing bag may be extended either up or down as desired, when down to go to a reservoir rebreathing bag which may be supported under the coat of the wearer, when up to go to a reservoir rebreathing bag which may be supported in

a compartment attached to the top of the helmet of the aviator.

It is a further object of our invention to provide oxygen delivering apparatus including a mask and symmetrically disposed breathing outlets at each side of the mask in conjunction with means for supporting a reservoir rebreathing bag upon the top of the helmet of the aviator and for connecting said breathing openings thereto.

It is a further object of our invention to provide a casing for a reservoir rebreathing bag adapted to be removably attached to the helmet of the aviator and to form a protected compartment warmed by the heat from the aviator's head in which the reservoir rebreathing bag will be positioned, said compartment being provided with apertures to atmosphere and an exhaling valve being positioned in the compartment whereby the same will be protected from freezing as it would be if worn under the coat of the aviator.

It is a further object of our invention to provide a specially constructed metallic or Bakelite saddle or reinforcing member which shall be light and strong and at the same time hold the face contacting portions of the mask firmly in position.

It is a further object of our invention to have the mask body formed very thin of dipped rubber and to support it with the aforesaid reinforcing saddle made up of spaced bands of metal and secured directly to the body of the mask.

It is a further object of our invention to have the saddle so formed that a portion thereof will engage about the outer contour of the mask but spaced therefrom a slight distance and to form said outer contours with a cross-sectional inward curve whereby together with the aforesaid reinforcing member for face-contacting portions of the mask will be adapted to conform to any contours of the face.

The full objects and advantages of our invention will appear in connection with the description as given in the specification and as shown in the drawings, and the novel features by which these desirable objects are attained will be particularly pointed out in the claims.

In the drawings:

Fig. 1 is a front elevation view of our oxygen administering apparatus with the reinforcing saddle in position and the rebreathing compartment secured to the top of the helmet.

Fig. 2 is a view similar to Fig. 1 without the reinforcing members showing a different method of connecting the mask to the head of the wearer and indicating the tubes extending downwardly to a reservoir rebreathing bag under the coat.

Fig. 3 is a detail view of a form of exhaling valve.

Fig. 4 is a substantially diagrammatic view of a source of oxygen supply.

Fig. 5 is a side elevation view showing the mask of Figs. 2 as worn with the tubes extending downwardly as in Fig. 2.

Fig. 6 is a partial side view of the mask as worn taken on a central sectional line.

Fig. 7 is a view of the mask from the inside with fastening means eliminated.

Fig. 8 is a sectional view taken on line 8-8 of Fig. 7.

Fig. 9 is a sectional view taken on line 9-9 of Fig. 8.

Fig. 10 is a part perspective view of a connector adapted to unite the breathing passages of the mask with the tubes leading to the reservoir rebreathing bag, which as above stated may be either up or down.

A mask body 11 is provided with a nose receiving portion 12 and lateral extensions 13 and 14 to which in the form shown in Figs. 2 and 5 are secured tabs 15 and 15' carrying a band 16 which is adapted to encircle the head of a wearer as indicated in Fig. 5. A central flattened turret 17 is adapted to hold a microphone indicated diagrammatically at 18, Fig. 6. The microphone turret 17 is substantially in the center of the mask structure. At each side thereof and preferably at slight angles, as shown in Figs. 2 and 7, are a pair of valve turrets 19 and 20. Within these turrets any suitable valve mechanism may be employed as for example discs 21 of sponge rubber. Such discs of sponge rubber provide a restriction in breathing, for either expiration or inspiration, of such a character that the reservoir rebreathing bag indicated at 22 in Fig. 1 will on expiration first be filled with the first part of exhalation gases which is that most heavily charged with oxygen and that thereafter the latter part of the exhalation will pass out through the sponge rubber valve discs 21. Correspondingly upon inspiration the reservoir rebreathing bag will first be emptied and then air may be drawn in through the sponge rubber valve discs 21, although restriction by said valve discs may be sufficient so that if abundant oxygen is being supplied there will be substantially no inspiration of air through the sponge rubber discs 21 on inhalation.

As clearly shown in Fig. 7, the openings 24 and 25 into valve turrets 19 and 20 are offset outwardly from the planes of the mask extensions 14 and 15, there being formed about said turret openings ear-shaped channels 26 and 27 which appear as double protuberant portions 28, 29 and 30, 31, Fig. 2. These protuberant portions are extended in a union portion 32 which surrounds a channel 33 having a curved outward wall 34 and a substantially straight inner wall 35. By this means a free passage of gas is provided to and from the chamber 36 inside of the mask and thence to and from the reservoir rebreathing bag by means which will now be described.

A feature of our invention which is of very great importance is the provision of an extension 23 of the mask body joining the extruded or protuberant portions 29 and 31 and so shaped and positioned as to underlie the chin of the wearer, as clearly shown, particularly in Figs. 5 and 6. This underlying arrangement anchors the entire mask upon the chin of the wearer and takes the stress of the fastening means about the head of the wearer such as shown at 16 in Fig. 5. It also has the added highly important function of receiving the terrific force of sudden reversals and upturns of the airplane, as in dive bombing or attack dives, or similar maneuvers. This force is transmitted directly to the lower jaw of the wearer whose head will normally under such conditions be held forward and down and thus will anchor the mask upon the junction of the lower jaws at the chin and resist any tendency to strip the mask from the face of the wearer. This effect will continue to anchor the mask, even though, as sometimes happens, the aviator's head is jerked backward at the time of the turn.

There also has been a substantial difficulty encountered with types of masks heretofore employed of finding suitable insulation between the mask body and the helmet of the aviator. Often there has been a space at the chin and along the sides of the margins of the mask where attack from severe cold can take place and frosting

results. The present structure, reaching clear under the chin and spreading over the cheeks of the wearer, actually underlies the margins of the aviator's helmet and produces a highly effective insulation.

It will be noted that the openings 33 extend outwardly and downwardly from the sides of the mask in effect spanning the lower portion of the face of the wearer. We may provide a connector piece 37 in detail such as shown in Fig. 10 which has a portion 38 adapted to be inserted in the openings 33 and extended from a shank portion 39 which in turn is extended by a suitable curve into a portion 40 which receives the breathing tubes 41 and 42. The tubes 41 and 42 may go downwardly as indicated in Figs. 2 and 5 and connect with a union 43 which has an outlet tube 44 going to the gas tube 45 leading to a reservoir rebreathing bag, not shown, which is held beneath the coat indicated at 46. An exhaling valve 47 of the type shown in detail in Fig. 3 may be incorporated in the line 45 under the coat of the wearer, as indicated in Fig. 5. An oxygen tube 48 leads from a supply of oxygen 49 with pressure regulated in a well-known manner to the casing member of valve 47 as shown in the lower part of Fig. 5, thus supplying oxygen to the breathing line at any desired or predetermined rate.

The exhaling valve 47 comprises a casing 50 formed with opposite tubular extensions 51 and 52 connected in the breathing line formed by the tubes 42 and 41, respectively, the oxygen tube 48 preferably having a continuation 53 in casing extension 51. The valve structure of known form comprises a valve seat 54, a valve disc 55 engageable therewith, a spring 56 holding the disc 55 in contact with valve seat 54 and a valve cap 57 holding the spring 56 in position and adapted to vary the pressure thereof upon valve disc 55 as may be desired.

When the sponge rubber valves 21 are employed exhaling valve 47, as positioned under the coat (or in the compartment above the helmet as hereinafter described), will act as an emergency valve. Normally it will be inoperative when the sponge rubber valves are functioning properly, but if through freezing or for any other cause the sponge rubber valves become choked or clogged to an extent so that exhalation cannot take place there, then the emergency exhaling valve 47 will come into play. Also it may under certain conditions be desirable to employ the mask for a closed circuit except for exhaling, in which case the turrets 19 and 20 may be closed by an impervious covering on the sponge rubber valve and only oxygen be supplied to the breather and exhalation taking place through the valve 47 positioned as above defined.

The members 37 as shown in Figs. 2 and 5 are turned downwardly for delivering to reservoir rebreathing bag below the chin and where desired specifically under the coat. These members 37 although asymmetrical can be moved to opposite sides and turned up as indicated in Fig. 1. They will then be connected with tubes 58 and 59 which join at 60 and 61 with connector nipples 62.

These nipples are parts of a light casting 63, Fig. 1, which is provided with a flange 64 adapted to be secured by bolts 65 to the aviator's helmet, which, following common practice, will be insulated as indicated at 66. The opening 67 through nipples 62 extends through channel 68 to a depending extension 69 adapted to receive a rebreathing bag 70 as shown in Fig. 1, the neck 76

71 of the rebreathing bag being secured to the extension 69 in a customary manner. The casting 63 is also provided with a channel 72 which communicates with oxygen tube 48.

5 An opening 73 above extension 68 leads into the chamber 74 inside the extension member 63 and connects with an exhalation valve similar to valve 47 shown in detail, which is located within the chamber 74. The material of the extension member 63 will be light but rigid and forms the compartment 74 in which is located the rebreathing bag 70 and the exhalation valve similar to valve 47, not shown in Fig. 1. Apertures 75 toward the lower part of chamber 74 open to atmosphere. These apertures are so positioned that the gases of exhalation will be caused to spread throughout chamber 74 and in that manner keep the exhaling valve and the walls of the rebreathing bag sufficiently warm so that freezing cannot take place within chamber 74. If desired to make more effective the warming of chamber 74, insulation, not shown, may be applied thereto in the manner of the insulation shown at 66 of Fig. 1.

25 As shown in Figs. 2 and 5 where the mask body 11 is composed of sufficiently heavy molded rubber the securing band 16 may be directly attached to the tabs 15 and 15' by means of rivets 76. However, we have found it desirable as adding to the comfort with which the mask can be worn and conducting to complete sealing of the mask at its face-contacting contour margins to form the mask quite thin of dipped rubber, and to provide in conjunction with said thin-walled 30 mask structure a saddle-like reenforcing member 77 such as is shown in general outline in Fig. 1. This member will be formed of light, strong material such as thin sheet metal or possibly some form of Bakelite. It comprises a rim portion 35 made up of nose clamping portions 78 and 79, cheek portions 80 and 81 and a chin portion 82 which underlies the chin-engaging portion of the mask. The respective portions 80 and 81 are united with the chin portion 82 by means of arched spanning portions 83 and 84 and the nose clamping portions 78 and 79 are connected with the chin portion 82 by means of central ribs 90 and 91 which are shaped as clearly shown to go about the microphone turret 17 and go inside 40 of the extruded portions 29, 31 and 28, 30, as shown in Figs. 6, 7 and 9. Further, the parts 90 and 91 may be provided with extensions 93 and 94 which take under the lip of the turret members 19 and 20 and aid in supporting them 45 against collapse.

50 The main mask body has, running around its entire contour limits, an edge portion 92 which is curved inwardly so as to show a substantially sharp edge as indicated at 95 and 96. The outer margins of the saddle 77 do not extend quite to the outer margins of the mask structure, leaving a part of the mask structure indicated at 97 and 98 which extends beyond said outer margins of the reenforcing saddle. The effect of these two devices, the curved edge contour and the extension of the body of the mask beyond the reenforcing framework is to bring the margins of the mask into secure sealing contact with the face of the wearer. The pressure of the rigid or at least semi-rigid springy outer portions of the reenforcing saddle is thus held away from the actual contacting margins of the reenforcing saddle frame, which insures not only a good fit but comfort in the wearing of the device.

55 As clearly indicated in Fig. 1, two sets of straps

99 and 100, and 101 and 102 are secured respectively to cheek members 80, 81 and the chin member 82 immediately below its junction with the transverse members 90 and 91. By these means the mask may be anchored very securely upon the face of the wearer. Although the tubes 41, 42 and 58, 59 for ease of drawing are shown as smooth-walled tubes, the common corrugated tubing, such as shown at 104 of Fig. 8 and 105 of Fig. 9 may be employed as is customary, since these corrugated tubes have greater resistance to collapse from outside pressure.

The mode of operation of our invention has been fairly well pointed out in the descriptive specification already given, and its marked advantages in use are quite apparent. Obviously the utility of the mask is dependent upon its easy cooperative relation with the oxygen supply and reservoir rebreathing bag. The structure of the mask permits balanced connection with the reservoir rebreathing bag either down as under the coat of the wearer or up as in the helmet of the aviator, and this connection is made in such a manner as not to interfere at all with the mask itself both as a protective covering to the face of the aviator, as a holder for the microphone and as a provider of a breathing chamber which permits free and easy balanced breathing either through mouth or nose at all times.

In addition to the above advantageous uses of the mask it cooperates with the goggles and helmet of the aviator so as completely to cover the face of the aviator and at all times protect from severe external cold. Furthermore, the form of the mask wherein a portion of it underlies the chin of the aviator and is held against the chin and beneath the margins of the aviator's helmet, taken with the method of securing the same by straps passing to the back of the head of the aviator effectively retains the mask in position so as to resist any and all severe stresses induced by flying maneuvers of aviators. At the same time the aviator, by merely inserting his fingers under the lower rim of the mask between the mask and the helmet, can strip the mask upwardly from his face, in the event of necessity of bailing out at high elevations and using a safety parachute outfit for supplying oxygen during that part of the parachute descent which is at too high altitudes and low barometric pressures for breathing safely without added oxygen.

We claim:

1. A mask structure comprising a body portion adapted to be held upon the face and providing a sealed breathing chamber therein, said mask structure being shaped and formed to enclose the cheeks and the chin of the wearer, raised portions in pairs above the respective cheek parts of the mask forming pairs of connected curved air-breathing channels open along their sides into the breathing chamber, each pair of said channels extending into a single passageway forming an opening from the breathing chamber in the mask body over face-contacting parts, and an extruded turret adapted to hold a valve structure within and encircled by each of said pairs of curved passageways.

2. Inhalation apparatus comprising a mask structure adapted to be held upon the face and providing a sealed breathing chamber therein, said mask structure being shaped and formed to enclose the cheeks and the chin of the wearer and being provided with outwardly directed openings from the sides of said breathing chamber, a casing adapted to be secured to the top

5 of the helmet of the wearer and forming a chamber, channels extending outwardly and downwardly along the sides of the casing and forming tube connections, a reservoir rebreathing bag connected with said channels within the casing, means for supplying oxygen to said rebreathing bag, and tubes connecting the mask openings with the openings through the casing, an exhaling valve located within the casing, and openings in the casing adapted to permit gases of exhalation to escape from the exhaling valve to pass out of said casing chamber.

3. A mask structure comprising a body portion formed of relatively thin rubber and adapted to be held upon the face and providing when so held a sealed breathing chamber therein, an extruded chamber formed at the center of the body portion and adapted to hold a microphone, a pair of extruded turrets laterally disposed relative to said microphone turret adapted to hold valve mechanism, a saddle reenforcing member having strip-like portions extending about all the contour margins of the mask body with transverse portions extending between the microphone turret and the respective valve turrets for holding the mask body in sealing position, and means for conveying respiratory gases to and from the breathing chamber.

4. A mask structure comprising a body portion formed of relatively thin rubber and adapted to be held upon the face and providing when so held a sealed breathing chamber therein, an extruded chamber formed at the center of the body portion and adapted to hold a microphone, a pair of extruded turrets laterally disposed relative to said microphone turret adapted to hold valve mechanism, a saddle reenforcing member having strip-like portions extending about all the contour margins of the mask body with transverse portions extending between the microphone turret and the respective valve turrets for holding the mask body in sealing position, the outer edges of said saddle reenforcing member being spaced from the outer edges of the mask body and said mask body having its edges inwardly curved, and means for conveying respiratory gases to and from the breathing chamber.

5. A mask structure comprising a body shaped and formed to contact the face of the wearer over the upper part of the nose, the cheeks and under the chin and forming a breathing chamber about the nose and mouth of a wearer, an extruded chamber sealed in said body and positioned at the center thereof adapted to hold a microphone, a pair of extruded turrets symmetrically disposed at each side and adapted to hold valve mechanism, the extruded turrets being continued into raised portions of the mask body extending to the margins of the mask body and forming symmetrically disposed downwardly-turned passages for conveying respiratory gases to and from said breathing chamber, and means for conveying the gases to said passageways including tubes and reversible connectors, whereby respiratory gases on inhalation and exhalation coming through the tubes and passages and through the valve mechanism in the turrets will be brought to and from the breathing passages of the wearer in an easy and uniformly commingled manner.

6. A mask structure comprising a body portion adapted to be held upon the face and providing a sealed breathing chamber therein, said mask structure being shaped and formed to enclose the cheeks and chin of the wearer, raised portions

above the cheek parts of the mask forming breathing passages curved rearwardly and downwardly, a turret extruded in the mask body and adapted to hold a valve structure positioned adjacent each of said passages and embraced by its curvature and connected therewith at its bottom part, and tubes connected with said curved passages for conveying respiratory gases to and from the same, whereby respiratory gases on inhalation and exhalation coming through the tubes and curved passages and through the valve mechanism in the turrets will be brought to and from the breathing passages of the wearer in an easy and uniformly commingled manner.

7. A mask structure comprising a body portion adapted to be held upon the face and providing a sealed breathing chamber therein, said mask structure being constructed and formed to enclose the cheeks and chin of the wearer, raised portions

5 above the cheek parts of the mask forming pairs of breathing passages on each side thereof respectively curved forwardly and rearwardly and uniting in a single passage extending downwardly, a turret extruded in the mask body and adapted to hold a valve structure positioned adjacent and so as to be embraced by the curvatures of said passageways and connected therewith at its bottom part, and tubes connected with the single extension of said curved passages for conveying respiratory gases to and from the same, whereby respiratory gases on inhalation and exhalation coming through the tubes and curved passages and through the valve mechanism in the turrets will be brought to and from the breathing passages of the wearer in an easy and uniformly commingled manner.
